UNITED STATES PATENT OFFICE

SIDNEY LEOPOLD PRICE, OF LONDON, ENGLAND

SOUND REPRODUCING DEVICE

Application filed February 12, 1930, Serial No. 427,855, and in Great Britain February 20, 1929.

This invention relates to electromagnetic sound reproducing devices of the type in which a diaphragm, cone or other member is adapted to be operated by an armature arranged in a magnetic field, the invention being particularly suitable for loud-speakers for use in connection with radio telephony or for gramophone pick-ups.

It is an object of the invention to provide a device of the type described which, while being of simple construction and inexpensive to manufacture, and which will give substantially uniform response to a wide band of frequencies, affords an improved tone, volume and quality of reproduction.

The invention consists broadly in mounting, suspending or supporting the armature directly or indirectly upon resilient or flexible or other means adapted to afford comparatively unrestricted freedom to vibrations communicated according to the various speech modifications of the energizing or controlling currents.

The invention comprises supporting the armature of a device of the type described from a support by means comprising a flexible or resilient or suspensory member (or members) which may be attached at one or both ends to the semi-rigid member or other support.

The armature may be directly supported by the support, being attached to the flexible or spring member or members, or the armature may be firmly attached to an armature carrying member, preferably of non-magnetic material, which is itself connected by the flexible or spring member or members to the semi-rigid member or main support.

The armature or intermediate member may be provided with a spindle for attachment to a diaphragm or cone of a loud-speaker, telephone receiver or the like, and the whole may be arranged in conjunction with a magnet system between which and the armature adjustment may be effected as is usual in the art.

According to one convenient method of carrying the invention into effect the armature may be attached, as by riveting, screwing or the like, to a semi-rigid armature carrying

member consisting, for example, of a stout strip or bar of phosphor bronze or other non-magnetic material, which member is hinged at or towards one end to a semi-rigid member or main support. Attached adjacent to the other end of the armature carrying member is the longer limb of a member in the form of a spring of roughly U-shape, while the shorter limb is secured through an aperture to the main support or supporting member.

A diaphragm spindle attached to the armature or armature bar may pass through a further aperture provided for its accommodation in the semi-rigid member. The hinge may be formed by a pair of lateral extensions on the intermediate bar or member bent or otherwise formed to embrace the semi-rigid member or fit into apertures in the said members, being further secured where necessary by soldering, brazing or otherwise.

In a modification of the above construction the hinge is replaced by a pivot or pin (or pins) on the armature carrying member, which pin may conveniently be seated in a depression formed in the semi-rigid member or be otherwise secured by aid of the pin or pins. Alternatively, the pivot may be carried by the semi-rigid support member and the seating by the armature carrying member.

In the above case and that foregoing, the armature may be positioned centrally of the armature carrying bar or towards or away from the spring connection.

According to another arrangement, the armature carrying member carrying the armature and spindle as indicated above, may be provided with resilient extensions at its extremities for attachment to the semi-rigid member. Such extensions may be in the form of strips of the material of the member not completely detached therefrom, or separate pieces may be soldered, riveted or otherwise attached to the member. The extensions may be parallel to each other and, where the member is rectangular, may be attached at diagonally opposite or at adjacent corners of the rectangle. The extensions may make any desirable angle with the

100

longitudinal edges of the armature carrying or intermediate member, such as an angle of 60°, or may be arranged in the line or as extensions of the longitudinal or transverse edges. Where the extensions are arranged at adjacent corners the extensions are preferably maintained in the same straight line, and the armature is preferably arranged on the member so that the centre of mass of the combination lies approximately on this line.

According to another form a plurality of resilient extensions may be provided at each end of the armature carrying or intermediate member for attachment to the semi-rigid member. In the case of a rectangular member a resilient extension may be arranged at each corner, preferably extending longitudinally, or a single extension or pin may be arranged at the mid points of the ends of the bar or member.

Alternatively, the armature carrying or intermediate member carrying the armature may be attached by a plurality of small leaf springs to the semi-rigid member; for example, a leaf or other spring may be attached adjacent to or at the extremities of the intermediate member. The leaf springs may be replaced by U-shaped springs having one arm longer than the other, the longer arm preferably passing through an aperture in the rigid member and being attached to the armature carrying or intermediate member or armature, the shorter arm being attached to the semi-rigid member.

The foregoing modes of resiliently supporting an armature carrying bar or intermediate member may be equally applied to the armature of the device in which case the intermediate member may be dispensed with and the armature resiliently mounted from a semi-rigid member or support.

In the accompanying drawing I have illustrated several forms that the invention may assume.

Figure 1 shows an armature carrying or intermediate member carrying the armature and mounted on a semi-rigid member.

Figure 2 is a view of another arrangement. Figure 3 shows the device in cross section arranged in a loud-speaker unit.

Figures 4 to 7 show various forms that the suspension of the armature carrying or intermediate member may take as viewed from the side to which the armature is affixed.

Figure 8 shows another method of suspension.

Like references indicate like parts throughout the figures.

Referring to Figure 1, 1 is a supporting member comprising a strip of phosphor bronze, brass or the like which is semi-rigid. It is provided with holes 2 for affixing to a support and with holes 3 and 4. Attached to the strip 1 by means of a hinge

5 and a spring 6 is an intermediate or armature carrying member 7, substantially rigid and of non-magnetic material. The spring 6 is attached as by soldering or riveting to the member 7 and the member 1 at the points 8 and 9, respectively, and one limb of it passes through the hole 3 which is sufficiently large to allow free movement of the limb of the spring. Attached to member 7 by any convenient means, such as brazing or riveting, is the armature 10, comprising a piece of soft iron. A rod 11 is also affixed to the intermediate member at a point about the centre of the armature, so as to pass through the hole 4, which is such as to afford clearance for unimpeded movement of the rod. The end of the rod is shown threaded at 12 so that attachment may be made to a diaphragm cone or the like.

In the arrangement shown in Figure 2 the intermediate or armature supporting member is dispensed with, the armature itself being directly attached to the spring 6 and the hinge 5. In order that the moving system may not be unduly massive the armature is shaped so as to comprise a portion of greater area 10 with two portions 14 and 15 of smaller area for connecting to the hinge 5 and the spring 6, respectively.

The hinge 5 may comprise steel wire of about 24 gauge of any convenient length passed through holes in and soldered or otherwise fastened to the member 7 or armature 10 and bent so as to embrace the member 1; or the wire may be passed through holes in and soldered to the member 1 so that the hinging effect is afforded by the resilience of the wire. In Figures 2 and 3 I have shown the wire passing through two suitable holes 5^a and 5^b in the armature and two corresponding holes in the member 1, one only, 1^a, of which is shown. The wire is then soldered in position. A single wire may of course replace the two lengths of wire. Again the hinge may take the form of small rods attached firmly to the member 7 or the armature and seating on convenient faces on the member 1 or vice versa. The spring 6 may be of phosphor bronze, steel or other suitable resilient material.

In Figure 3 the device shown in Figure 2 is illustrated in position in a loud-speaker unit. Screws 16 connect the member 1 to the casing 17 of the unit which is provided with the usual permanent magnets 21 and pole pieces 20 carrying coils 19. An arrangement for adjusting the distance between the pole pieces and the armature 10 is provided, adjustment being made by the knurled headed screw 22.

In Figures 4 to 7 I have shown the armature 10 attached to the member 7 as in the case of Figure 1. Instead, however, of providing a hinge or pivot at one end of the member, I provide resilient extensions at

both ends of the member 7 lying in the plane of said member 7 for direct attachment to struts or the like extending outwardly from the face of the member 1. The extensions 5 25, 27, and 31 are formed of the material of the member 7 and are of such section as to give the required resiliency. The extensions 29 are pieces of suitable wire or strip attached to the member 7 by soldering or otherwise. In the case of Figure 7 where the supporting springs 31 are to one side of the centre of the intermediate member, the armature 10 is displaced in order that the centre of 10 gravity of the whole lies in the lines of the springs. The extensions are attached to the member 1. At the points 8 I attach the longer limb of a spring 6 the other end of which is attached to a fixed member or support as in the case of Figures 1 to 3. The 20 spring 6 is shown arranged at an angle to the length of the member 7 so as to avoid the rod 11.

In Figure 8 I have shown another way of supporting the armature 10 directly by two 25 springs 32 which are attached to the armature and the bar 1 in the same way as has been indicated in the case of the arrangement shown in Figures 2 and 3. In this case also the hinge is not employed.

30 In the above cases, I may arrange the spring 6 so that it is below the supporting member; in which case the longer limb of the spring would be attached to the member 1 and the shorter limb to the member 7 or the 35 armature 10.

It will be appreciated that where I have shown the armature directly suspended from the bar 1, the alternative arrangement of suspending the armature carrying or intermediate member with the armature attached is possible and, similarly, the methods shown 40 of suspending the member 7 may be applied to the armature 10. Also it will be understood that the member 1 may form part of an 45 electromagnetic system and assume other forms than that shown.

While the invention has been described in connection with electromagnetic devices it may be applied for a purely mechanical arrangement such as found in sound boxes of 50 gramophones and the like, in which case the resilient mounting would be applied to the support of the needle and intermediate the latter and the diaphragm. For example, the 55 member 1 may constitute part of the sound box or may be attached thereto. The stylus bar may be resiliently supported as in the case of the armature described above, being either hinged adjacent to the end farthest 60 from the needle or stylus holder, or supported by a plurality of springs or resilient extensions.

According to a modification I may attach 65 the armature or armature-carrying member to the support by one or more wires or the

like struts projecting substantially normally therefrom, two being arranged towards one end of the armature or armature-carrying member and one towards the opposite end thereof and preferably equidistant from the other two. I may make the support of a resilient bar, frame or the like, attached at its ends to a substantially rigid supporting structure. Again, I may increase the length of the wires or struts so that they 70 become more resilient and so render unnecessary any further resilient member. Where, as in the latter case, I rely on the resiliency of the wires or struts, I may arrange them at an angle to the plane of the armature or 75 armature-carrying member so that the resilient effect is obtained by slight bending of the wires.

Where in the specification and claims I have used the term "U-shaped spring" or "U-shaped resilient member" it is to be understood I include any spring having parallel limbs, whether the limbs are joined by a simple bend or one or more coils of the material.

Having now described my invention, what I claim as new and desire to secure by Letters Patent is:—

1. The method of supporting the magnetic armature of an electromagnetic device adapted for use in the reproduction of sound, which comprises suspending the armature having connected thereto a diaphragm actuating stylus from a semi-rigid member in the form of a reed by means comprising at least one resilient member, whereby to afford to the armature comparatively unrestricted freedom to vibrate.

2. The method of supporting the magnetic armature of an electromagnetic device adapted for use in the reproduction of sound, which comprises suspending a member carrying the armature, to which is connected a diaphragm actuating stylus, from a semi-rigid member in the form of a reed by means comprising at 100 least one resilient member, whereby to afford to the armature comparatively unrestricted freedom to vibrate.

3. In an electromagnetic device for use in the reproduction of sound, a semi-rigid supporting member from which a magnetic armature is suspended and spaced and a diaphragm actuating stylus connected to the armature but having no positive connection with the supporting member.

4. In an electromagnetic device for use in the reproduction of sound, a semi-rigid supporting member in the form of a reed, from which a magnetic armature is suspended and spaced and a diaphragm actuating stylus connected to the armature but having no positive connection with the supporting member.

5. In an electromagnetic device for use in the reproduction of sound, a magnetic armature, a semi-rigid supporting member in the

form of a reed from which an armature carrying member is suspended and spaced and a diaphragm actuating stylus connected to the armature having no positive connection with 5 the supporting member.

6. In an electromagnetic device adapted for use in the reproduction of sound, a vibratory member including a magnetic armature, a diaphragm actuating stylus connected to 10 the vibratory member, a semi-rigid supporting member in the form of a reed and at least one resilient member attaching the vibratory member to the semi-rigid supporting member so as to afford to the vibratory member 15 comparatively unrestricted freedom to vibrate.

7. In an electromagnetic device adapted for use in the reproduction of sound, a vibratory member including a magnetic armature, a magnet system arranged adjacent the armature, a diaphragm actuating stylus connected to the vibratory member, a semi-rigid supporting member in the form of a reed and at least one resilient member attaching the vibratory member to the semi-rigid supporting member so as to afford to the vibratory member 25 comparatively unrestricted freedom to vibrate.

8. In an electromagnetic device adapted for use in the reproduction of sound, a vibratory member including a magnetic armature, a diaphragm actuating stylus connected to the vibratory member, a semi-rigid supporting member in the form of a reed, a hinge adjacent to one end of the vibratory member 35 connecting said vibratory member to the semi-rigid supporting member and a resilient connection between the vibratory member and the semi-rigid supporting member arranged adjacent to the other end of said vibratory member.

9. In an electromagnetic device adapted for use in the reproduction of sound, a vibratory member including a magnetic armature, an electromagnet system arranged adjacent the armature, a diaphragm actuating stylus connected to the vibratory member, a semi-rigid supporting member in the form of a reed, a hinge adjacent to one end of the vibratory member connecting said vibratory 50 member to the semi-rigid supporting member and a resilient connection between the vibratory member and the semi-rigid supporting member arranged adjacent to the other end of said vibratory member.

55 10. In an electromagnetic device adapted for use in the reproduction of sound, a vibratory member including a magnetic armature, a diaphragm actuating stylus connected to the vibratory member, a semi-rigid supporting member in the form of a reed and a plurality of resilient springs attaching the vibratory member to the semi-rigid supporting member so as to afford to the vibratory member 60 comparatively unrestricted freedom to vibrate.

11. In an electromagnetic device adapted for use in the reproduction of sound, a vibratory member including a magnetic armature, a magnet system arranged adjacent the armature, a diaphragm actuating stylus connected to the vibratory member, a semi-rigid supporting member in the form of a reed and a plurality of resilient springs attaching the vibratory member to the semi-rigid supporting member so as to afford to the vibratory member comparatively unrestricted freedom to vibrate. 70

12. In an electromagnetic device adapted for use in the reproduction of sound, a vibratory member including a magnetic armature, and an intermediate member carrying the armature, a magnet system arranged adjacent the armature, a diaphragm actuating stylus connected to the vibratory member, a semi-rigid supporting member in the form of a reed and resilient extensions on said intermediate member, attaching the vibratory member to the semi-rigid supporting member so as to afford to the vibratory member comparatively unrestricted freedom to 75 vibrate. 80

13. In an electromagnetic device adapted for use in the reproduction of sound, a vibratory member including a magnetic armature, a magnet system arranged adjacent the armature, a diaphragm actuating stylus connected to the vibratory member, a semi-rigid supporting member in the form of a reed and a pair of U-shaped springs attaching the vibratory member to the semi-rigid supporting member so as to afford to the vibratory member 90 comparatively unrestricted freedom to vibrate. 95

14. In an electromagnetic device for reproducing sound, means for producing a magnetic field, means for causing variations in said magnetic field, a semi-rigid support in the form of a reed, a vibratory member comprising a magnetic armature and at least one resilient connection between said semi-rigid support and the vibratory member supporting the vibratory member with the armature in the magnetic field. 105

15. In an electromagnetic device for reproducing sound, means for producing a magnetic field, means for causing variations in said magnetic field, a vibratory member comprising a magnetic armature, a diaphragm actuating stylus attached to the vibratory member, a semi-rigid support in the form of a reed from which the vibratory member is suspended and at least one U-shaped resilient connection between said semi-rigid support and the vibratory member supporting the vibratory member with the armature in the magnetic field. 115

16. In an electromagnetic device for reproducing sound, means for producing a magnetic field, means for causing variations in said magnetic field, a semi-rigid support, 120

a vibratory member comprising a magnetic armature and a U-shaped resilient member and a hinge member between said semi-rigid support and the vibratory member supporting the vibratory member with the armature in the magnetic field.

In testimony whereof I have signed my name to this specification.

SIDNEY LEOPOLD PRICE.
